(57) **CLAIM**

The ornamental design for a salad server, as shown and described.

DESCRIPTION

FIG. 1 is a top, rear and left side perspective view of the salad server comprising a salad server spoon and a salad server fork positioned on top of the salad server spoon;

FIG. 2 is a top view thereof;

FIG. 3 is a bottom view thereof;

FIG. 4 is a left side view thereof;

FIG. 5 is a right side view thereof;

FIG. 6 is a rear view thereof; and,

FIG. 7 is a front view thereof.

The broken lines shown in the drawing views are included for illustrative purposes only and are not intended to limit the claimed design.
